Patented Feb. 7, 1922.

UNITED STATES PATENT OFFICE.

ALEXANDER V. WILSON, OF BAR HARBOR, MAINE.

DRIVING MEANS FOR SPRING MOTORS.

1,405,649.

Specification of Letters Patent. Patented Feb. 7, 1922.

Application filed January 26, 1918. Serial No. 213,986.

To all whom it may concern:

Be it known that I, ALEXANDER V. WILSON, a citizen of the United States, and a resident of Bar Harbor, in the county of 5 Hancock and State of Maine, have invented a new and useful Improvement in Driving Means for Spring Motors, of which the following is a specification.

My invention relates to improvements in 10 motors, being more particularly an improvement in spring motors, and it consists in the constructions, combinations and arrangements herein described and claimed.

An object of my invention is to provide 15 a motor including a power spring which is adapted to drive a power shaft, and which is arranged to be rewound either continuously by a suitable winding mechanism, or intermittently by a coacting strike plate and 20 lever arrangement.

Another object of the invention is to provide 25 a spring motor as described including a rewinding lever with an arrangement of strike plates so disposed in a floor or other surface, that persons walking across the strike plate will cause by their weight, the automatic rewinding of the spring.

Another object of the invention consists 30 in the peculiar formation of the double action pawl which is so designed to always engage the ratchet irrespective of its circumferential relationship to the ratchet.

Other objects and advantages will appear 35 in the following specification, reference being had to the accompanying drawing in which:

Figure 1 is a front elevation of the spring motor.

Figure 2 is a cross section on the line 2—2 40 of Figure 1.

Figure 3 is a detail section of the drive shaft with the coacting ratchet and spring; and

Figure 4 is a detail view of the double acting pawl.

In carrying out my invention I provide a power shaft 1 mounted in bearings 2 on top of standards 3 supported on a suitable base or platform 4. The power shaft 1 has a 50 large gear 5 in the middle and cranks 6 on

the ends. The purpose of the power shaft 1 is to provide the medium through which the power generated by the power spring is transferred to an external employment. To this end either the large gear or the cranks 55 described may be used, and if it be not desirable to use these devices, other and more suitable means for taking off the power may be connected with the shaft.

Mounted in a bearing 7 in one of the 60 standards 3 is a drive shaft 8 with a square portion 9 on the exposed end. The other end of the shaft 8 is supported in a standard 10 in which the anchor pin 11 on which one end of the power spring 12 is secured, is 65 mounted.

The other end of the power spring 12 is secured to the drive shaft 8 as indicated in Figure 2. The rotation of the drive shaft 8 in a clockwise direction in Figure 2, winds 70 the spring. Upon unwinding of the spring, the drive shaft 8 is driven in a counter-clockwise direction and the power thus derived is taken off by an arrangement of gears having connection with the power 75 shaft 1.

This arrangement of gears includes the master gear 13 loose upon the drive shaft 8 adjacent to the power spring 12. The master gear 13 meshes with a pinion 14 on the 80 power shaft 1. Fixed upon the drive shaft 8 at the other side of the master gear 13 is a broad ratchet 15. The ratchet 15 is made relatively broad as will be observed by comparison between the ratchet and the coacting 85 pawl shown in Figure 3, for the purpose of accommodating the operating lever about to be described.

The double acting pawl 16 is pivoted at 17 to a hub or boss on one of the spokes of 90 the master gear 13. The heels 18 and 18^a of the pawl engage the teeth of the ratchet and constitute the medium through which the master gear 13 is rotated in the counter-clockwise direction upon unwinding of the 95 power spring 12. The pawl 16 is of a peculiar design as shown in Figure 4, in that it includes a head 19 making the pawl heavier on one side of the pivot than on the other.

This peculiar design was adopted after considerable experimentation, and is found to possess the important and necessary feature of holding either one or the other of the heels in contact with an adjacent tooth of the ratchet, irrespective of the circumferential relationship of the pawl to the ratchet. It will be understood that it makes no difference whether the pawl is at the top, bottom, or sides of the ratchet, still one of the heels will engage one of the teeth at all times. Incidentally, it should be observed that the distance between the heels of the pawl is such that when one of the heels engages a tooth, the other heel is just half way between an adjacent pair of the teeth. This is well illustrated in Figure 4, and the feature thus represented constitutes the provision of an effectively operating escapement mechanism.

Fulcrumed in a bracket 20 on a movable standard 21 is an operating lever 22 with a pawl 23 on one end for driving the ratchet and drive shaft around. The lever 22 has a series of holes 24 so that the leverage may be adjusted. The standard 21 has a square projection which fits into any one of a series of square recesses 25 in the platform 4. These recesses are directly below the holes 24, this arrangement preserving the proper location of the pawl 23 with respect to the ratchet 15, no matter to which of the adjustments the standard 21 is moved. The pawl 23 is mounted in a bracket on the end of the lever 22 and a spring presses the pawl into contact with the ratchet.

Disposed on the end of the lever 22, is a strike plate 26. In the present instance the strike plate 26 is exposed in an opening in the floor 27, the illustration being intended to show that the lever 22 is susceptible to being depressed a certain distance each time a person steps on the strike plate. By this means actual power represented by the weight of the person and otherwise totally lost, is stored in the power spring 12 as will be readily understood in Figure 2. A coil spring 28 disposed between the end of the lever 22 and an abutment 29, serves to prevent the sudden descent of the lever upon being stepped on, and also to return the strike plate to its former position in the floor opening.

A stop 30 limits the downward movement of the front end of the lever. The stop 30 is adjustable by means of the set screw 31 which binds against the stop where the stop passes through the square collar on the abutment 29. The strike plate 26 may also be arranged alongside of a railroad track in such a position that the flange of the wheel 32 will depress the end of the lever and accordingly operate the spring motor. The obvious advantage of such an arrange-

ment is, that the lever will be pressed many times during the passage of a train, consequently offering a ready means for again storing considerable energy otherwise lost.

The operation of the spring motor will be readily understood from the foregoing description, but a brief review is thought to be of advantage. One of the important features of the invention consists of the adaptability of the device to such circumstances where it may conveniently be employed or installed to obtain the benefit of the successive depressions of the operating lever as for instance, by persons walking across the floor, while the arrangement of the strike plate 26 on the end of the lever in the present instance is of the simplest form, in actual practice, the strike plates may be so arranged in a floor that the weight of the persons walking across the floor may be utilized to the best advantage. Similarly, the strike plates in the event that a plurality is used, may be arranged alongside of a railroad track to multiply the depressions of the operating lever 22 and consequently obtain many rewinding impulses for the spring.

The reciprocations of the operating lever 22 revolve the drive shaft 8 in a clockwise direction, through the medium of the pawl 23 and the ratchet 15. The power spring 12 is thus wound. Upon unwinding of the spring, the drive shaft 8 is rotated in a counter-clockwise direction, whereupon the power shaft 1 is driven in a clockwise direction through the medium of the master gear 13 and pinion 14. Although the master gear 13 is loose upon the drive shaft 8, the constant engagement of one of the heels of the pawl 16 with the ratchet 15, constitutes a fixed connection between the drive shaft and the master gear during the unwinding of the power spring.

While the construction and arrangement of the motor as hereinbefore described, is that of a generally preferred form, obviously, modifications and changes may be made without departing from the spirit of the invention or the scope of the claims.

I claim:—

1. In a spring motor, the combination of the drive shaft, a ratchet fixed on the drive shaft, a master gear loose on the drive shaft adjacent to the ratchet, and a pawl pivoted to the master gear, said pawl including a pair of heels one of the heels being disposed midway of a pair of the ratchet teeth while the other is in engagement with a tooth, and a head embodied in the pawl for holding one or the other of the heels in contact with an adjacent tooth irrespective of the circumferential position of the pawl.

2. The combination of a driving ratchet of a spring motor, and an adjacently pivoted

pawl with a ratchet engaging heel at each side of the pivot, provided with a weighted portion arranged to hold one of the heels in engagement with the ratchet regardless of the circumferential position of the pawl with respect to the ratchet.

3. The combination of a master gear in a spring motor, a driving ratchet, and a

double-heeled pawl pivotally mounted on said gear, with a weighted portion arranged to hold one of the heels in engagement with the ratchet regardless of the circumferential position of the pawl with respect to the ratchet.

ALEXANDER V. WILSON.
